RAIL ANCHOR

Robert Andrew Thomann, Clayton, Mo., assignor,
by direct and mesne assignments, of forty-
seven per cent to Walter Schroeder, Wayne
County, Mich.

Application March 27, 1941, Serial No. 385,527

5 Claims. (Cl. 238—330)

This invention relates to a rail anchor designed primarily for use in connection with railway track rails, but it is to be understood that an anchor in accordance with this invention is for employment in any connection for which it may be found applicable.

The invention aims to provide, in a manner as hereinafter set forth, an anchor of the class referred to, to prevent the creeping of a railway track rail when installed relative to the latter.

The invention further aims to provide, in a manner as hereinafter set forth, a rail anchor having inherent means for locking it to the base of a railway track rail when the anchor is installed.

The invention further aims to provide, in a manner as hereinafter set forth, a rail anchor having inherent means for locking it in overlapped relation with respect to the base of a railway track rail.

The invention further aims to provide, in a manner as hereinafter set forth, a rail anchor including a base, a clamping jaw at one end of the latter for overlapping having a tight fit with the lower and upper faces of one side of the base flange of a railway track rail, and means extending from the other end of the base and engaging with the edge of the other side of the base flange of the railway rail for locking the jaw in position whereby the anchor will be fixedly secured to the railway track rail in depending relation with respect to the latter and to the cross tie to prevent the rail from creeping.

The invention further aims to provide, in a manner as hereinafter set forth, an anchor for the purpose referred to, including a jaw for overlapping the base flange of the railway rail and means for locking the jaw in such position.

The invention further aims to provide, in a manner as hereinafter set forth, an anchor for the purpose referred to, and of a form which, when installed relative to a railway track rail, will prevent tie plate contact.

The invention further aims to provide, in a manner as hereinafter set forth, a rail anchor which is simple in construction and arrangement, strong, durable, compact, thoroughly efficient in its use, readily installed with respect to a railway track rail without tie plate contact, and comparatively inexpensive to manufacture.

Embodying the aims aforesaid, and others which may be hereinafter set forth, the invention consists of the novel construction, combination and arrangement of parts, as will be more specifically described and illustrated in

the accompanying drawing, wherein is shown an embodiment of the invention, but it is to be understood that changes, variations and modifications may be resorted to which will come within the scope of the invention, as claimed.

In the drawing:

Figure 1 is a vertical sectional view of a railway track rail, with the latter mounted on a tie plate supported upon a cross tie, and showing the adaptation of a rail anchor, in accordance with this invention, with respect to the track rail, tie plate and cross tie, the anchor plate and tie being in side elevation.

Figure 2 is a top plan view of the structure shown by Figure 1, with the rail shown in dot and dash lines; and

Figure 3 is a side elevation of the anchor.

With reference to the drawing, a railway track rail is generally indicated at 5 and its head, web and base are indicated at 6, 7 and 8 respectively. As is well known, the base 8 is in the form of a pair of oppositely extending flanges 9, 10 disposed in lateral relation with respect to the web 7. The edges of the flanges 9, 10, are indicated at 11, 12 respectively. The upper faces of the flanges 9, 10 incline downwardly from the web 7 to the edges 11 and 12 respectively. The lower face of the base 8 is flat and is shown seated upon a metallic tie plate 12a mounted on a wooden cross tie 13. The rail 9 and tie plate 12a are secured to the cross tie 13 in a known manner.

The rail anchor, in accordance with this invention, is a one-piece body of any suitable metallic material. Preferably, the anchor will be made of any suitable carbon steel to give desired strength and resiliency when it is installed relative to the rail. The anchor includes a horizontally disposed base 14, a clamping jaw 15 and a locking arm 16.

The base 14 gradually decreases in width from the outer end 17 to the inner end 18. The outer end 17 is squared. The inner end 18 is slightly rounded. The top of the base is of greater length than the bottom 19. The latter is flat. The base is substantially of trapezium contour in plan and of substantially rectangular form in side elevation with the inner end of each side upon a slight curve. The base has its width and length greater than the height thereof. The base 14 has the outer portion 20 of the top disposed at a higher level than the inner portion 21 thereof. The portions 20, 21 are separated by a transverse groove 22 of concave contour. The providing of the top of the base 14 of two levels

forms the base of a high portion and a low portion.

The body of the jaw 15 is of less cross sectional width than the transverse cross sectional width of said base 14. The jaw 15 includes a straight lower portion 23 which is integral at the lower side with the top portion 20 of base 14, and it is spaced equi-distant from the sides of base 14. The inner end of portion 23 is curved and forms an upward continuation of the wall of the groove 22. The jaw 15 includes a vertically disposed intermediate or outer portion 24 of arcuate contour and which may be termed a half round portion. The jaw 15 includes an upper portion 25 which is downwardly inclined to the horizontal, and it is disposed over, spaced from and of greater length than the portion 23. The inner terminal part of the said jaw portion 25 is arranged in inwardly extended relation with respect to the jaw portion 23. The outer end of the latter merges into the lower end of jaw portion 24. The outer end of jaw portion 25 merges into the upper end of jaw portion 24. The jaw portion 25 gradually increases in width from its point of emergence with jaw portion 24 towards its free end.

The upper face or edge of the jaw portion 23 is straight and it is employed for binding against the lower face of the base 8 of the rail 5. The inner face or edge of jaw portion 24 is curved and it is to oppose the outer edge of a flange 9 or 10. The inner face or edge of jaw portion 25 has an inclined front part 26 and a straight rear part 27. The latter is for riding and binding on the upper surface of a flange 9 or 10. The normal position of the jaw 15 is as shown by Figure 3, and when positioned on a flange 9 or 10 the jaw portion 25 is extended relative to the jaw portion 23 such as is shown by Figure 1. The jaw 15 is driven on a flange 9 or 10 and when driven upon a flange, the jaw will appear as shown by Figure 1 with respect to the flange 9 of the rail 5. Owing to the manner in which the jaw 15 is constructed, the portions 23, 25, when driven on a base flange, will tightly clamp on the upper and lower faces of the base 8. The front edge part 26 of jaw portion 25 is clear of rail 5 when the jaw 15 is clamped to the latter. Depending from the jaw portion 24, and integral with the outer end 17 of base 14, is a reinforcing web 28. The sides of the jaw 15 are grooved as at 29 for decreasing the amount of material forming the jaw without impairing the strength of the latter. The jaw 15, prior to its being driven on the base 8, of the rail 5, will have the space between edge part 27 of jaw portion 25 and the upper edge or face of jaw portion 23 such that it will require the spreading of jaw portion 25 relative to jaw portion 23 to position the clamp properly on the rail.

The locking arm 16 is of a length to engage the edge and lower face of a flange 9 or 10, for the purpose of locking the jaw on the rail 5. The arm 16 includes a bar-like member 30 which, at its inner end, is integral with the upper portion of the end 18 of the base 14. The member 30 includes a part 31 which extends at an upward inclination with respect to the base 14 and merges into a horizontally disposed angle shaped part 32. The inner end of member 30 is disposed centrally of the upper end of base 14. The member 30 preferably will be of rectangular contour in transverse section and of less width than the jaw 15. The angle shaped part 32 consists of a flat horizontal leg 33 and a vertical leg 34 at the

outer end of the leg 33. The upper face 35 of leg 33 constitutes a seat. The leg 34 constitutes a locking or latching member. The upper end of part 31 of the arm 16 merges into the inner end 5 of the leg 33 of the part 32. The latter is disposed at an angle to the part 31.

When the anchor is to be installed with respect to the rail 5 and it will be assumed it is to have its jaw 15 clamped on the flange 9 of rail 10 base 8, the jaw 15 is arranged on flange 9 in a position whereby the rear end of jaw portion 25 will be at the dot and dash line 36 and the high point of the locking member will bear against the lower face of flange 10 at the dot and dash line 37. The outer side face of edge of the jaw portion 24 is then impacted by any suitable instrument for the purpose of setting the jaw 15 relative to flange 9 or 10, after which it is driven on the flange by sledging at base end 17 or jaw 20 portion 28, to clamping or binding engagement with the rail. As the jaw is driven on the rail, the arm 16 will be moved transversely of the 25 bottom of the rail until the locking member or leg 34 snaps over and engages the edge 12 of flange 10, with the latter engaging the seat provided by the leg 33, and at this time the driving action is discontinued whereby the anchor is locked to the rail 5.

Owing to the manner in which the jaw 15 and locking arm 16 are formed and arranged relatively to the base 14, they will not contact with the tie plate 12a as they are spaced from the latter. Owing to the tapered form of the base 14 it provides for its inner end hitting the cross 35 tie just before its outer end throwing the first main strength at said inner end where the anchor is on the rail solid and secure.

To remove the anchor, strike a holding blow down on 34 and if needed, hit the jaw on one side to remove it.

The base 14 hits the wooden cross tie 13, but it must have considerable wear before the jaw 15 could hit the tie plate 12a. Sometimes tie plates are wider than the wooden cross tie, or the tie plates extend out beyond the cross tie and the jaws of some anchors but the tie plate and the wave motion of the rail when traffic is passing thereover, rocks the cross tie in the ballast and if some ballast is loose it will work under the cross tie or the tie will work away from the ballast thus making it necessary for track men to retamp the ballast and which entails more or less labor cost. Also the wave motion of the rail, rubbing the jaw of the anchor band against the tie plate, causes the spikes to be distorted and loosened. Owing to the construction and arrangement of an anchor, in accordance with this invention, tie plate contact, spike loosening and tie rocking are prevented.

What I claim is:

1. An anchor for a railway rail comprising a horizontally disposed base substantially of trapezium contour in plan and of substantially rectangular form in side elevation for disposing in juxtaposition to one side of a cross tie, a horizontally disposed inwardly opening clamping jaw for binding against one side of the base flange of the rail, said jaw being disposed over and in upwardly extended relation with respect to the top of and offset relative to the outer end of said base, a resilient locking arm for correlation with an edge of said base flange disposed substantially in laterally extended relation with respect to the base and in a direction from said

jaw, and said jaw being spaced laterally inwardly from each side of the base.

2. An anchor for a railway rail comprising a horizontally disposed base for disposing in juxtaposition to one side of a cross tie and of substantially rectangular contour in side elevation, a horizontally disposed inwardly opening clamping jaw for binding against one side of the base flange of the rail, said jaw being disposed over and in upwardly extended relation with respect to and integral with the outer side portion of the top of said base, said jaw being offset relative to the outer end of said base, a resilient locking arm for correlation with an edge of said base flange disposed substantially in laterally extended relation with respect to the base and in a direction from said jaw, said arm being integral with the upper portion of the other end of said base, said base decreasing in width from said jaw to said arm, and said jaw and arm being spaced inwardly from each side of the base.

3. An anchor for a railway rail comprising a solid horizontally disposed base for disposing in juxtaposition to one side of a cross tie and formed of a top, a bottom, a pair of sides, an outer end and an inner end, a horizontally disposed inwardly opening clamping jaw for binding against one side of the base flange of the rail, said jaw being disposed in upwardly extended relation with respect to and integral with a portion of the top of said base, and a resilient locking arm integral with the inner end of said base for correlation with an edge of said base flange disposed substantially in laterally extended upwardly in-

clined relation with respect to the top of said base and in a direction from said jaw, the sides of said arm and jaw being spaced inwardly from both sides of said base.

4. A rail anchor comprising a horizontally disposed base including a top, a pair of sides, a bottom, an outer end and an inner end, a horizontally disposed inwardly opening upstanding clamping jaw integral with a part of the top of said base, said jaw being offset with respect to the outer end of said base and having its sides spaced equi-distant inwardly from the sides of the base, and a resilient locking arm integral with the inner end of said base, extending in a direction from said jaw and having its sides spaced equidistant inwardly from the side of said base, said jaw and arm being of materially less width than the width of said base.

5. A rail anchor comprising a horizontally disposed base including a top, a pair of sides, a bottom, an outer end and an inner end, a horizontally disposed inwardly opening upstanding clamping jaw integral with a part of the top of said base, said jaw being offset with respect to the outer end of said base and having its sides spaced equi-distant inwardly from the sides of the base, a resilient locking arm integral with the inner end of said base, extending in a direction from said jaw and having its sides spaced equi-distant inwardly from the sides of said base, said jaw and arm being of materially less width than the width of said base, and said base gradually decreasing in width from its outer to its inner end.

ROBERT ANDREW THOMANN.
